ATTORNEYS.

UNITED STATES PATENT OFFICE.

FRANK D. GOODWIN, OF BANGOR, MAINE, ASSIGNOR OF ONE-HALF TO
HARRY A. CHAPMAN, OF SAME PLACE.

DESIGN FOR A STAIR-CORNER GUARD.

SPECIFICATION forming part of Design No. 30,252, dated February 21, 1899.

Application filed December 30, 1898. Serial No. 700,770. Term of patent 14 years.

To all whom it may concern:

Be it known that I, FRANK D. GOODWIN, of Bangor, in the county of Penobscot and State of Maine, have invented and produced a new and original Design for Stair-Corner Guards, of which the following is a specification, reference being had to the accompanying drawings, forming a part thereof, in which—

Figure 1 is a perspective view of a stair-corner guard embodying the features of my design, the view being taken from the front of the device; and Fig. 2 is a perspective view taken from the rear of the device.

The design consists of a triangular plate A, having straight and parallel front and rear

faces, the edges of the plate appearing beveled rearwardly, an extension B, circular in cross-section and extending at a right angle to the rear face of the plate, and a depression a, appearing at the front of the plate opposite the extension B, which latter appears tubular, the opening 10 therein leading to the depression a at the front of the plate.

I claim—

The design for a stair-corner guard herein shown and described.

FRANK D. GOODWIN.
